UNITED STATES PATENT OFFICE.

ISAAC MARKS, OF HARVEY, ILLINOIS.

RECEPTACLE.

Application filed November 18, 1922. Serial No. 600,672.

To all whom it may concern:

Be it known that I, ISAAC MARKS, a citizen of the United States of America, residing at Harvey, in the county of Cook, State of Illinois, have invented certain new and useful Improvements in Receptacles; and I do hereby declare that the following is a full, clear, concise, and exact description of the invention, such as will enable others skilled in the art to which it appertains to make and use the same.

This invention relates to improvements in receptacles, having for an object to provide a watch-glass receptacle of such construction as will permit the arrangement, in classified order, of watch-glasses of different sizes therein, thus facilitating the housing of the same as well as the selections of a particular or desired size of watch-glass.

Another and equally important object of the invention is to provide a receptacle wherein different sizes of watch-glasses received therein will be displayed to the full view of a person upon opening of the receptacle and yet, will in no way have their classified order disturbed during such opening or displaying.

Other objects will be in part obvious and in part pointed out hereinafter.

In order that the invention and its mode of operation may be readily understood by persons skilled in the art, I have in the accompanying illustrative drawings, and in the detailed following description based thereon, set out one possible embodiment of the same.

In these drawings:—

Figure 1 is a plan view of the improved receptacle with the cover therefor in its open position;

Figure 2 is a vertical longitudinal section through the improved receptacle;

Figure 3 is a vertical transverse section therethrough; and,

Figure 4 is a fragmentary detail in elevation showing the particular type of catch employed for securing the cover in its closed position.

Having more particular reference to the drawings, in connection with which like characters of reference will designate corresponding parts throughout, the improved receptacle may be stated to comprise a body 1, substantially rectangular in shape and having a longitudinally disposed tapered pocket 2 formed therein, substantially semi-

circular in cross section as clearly shown in the Figure 3. This tapered pocket 2 is divided into a plurality of compartments by means of transversely disposed semi-circular partitions generally indicated by the numeral 3, the marginal portions of which are adapted to be engaged in correspondingly formed grooves in the pocket as shown in the Figure 2.

A cover 4 is provided for the body 1 and as will be noted, is of a size and shape corresponding thereto, being hinged to the rearward upper marginal portion of the body 1, as indicated by the numeral 5 and having a pivoted catch arm 6 mounted upon the intermediate portion of its forward marginal portion adapted to be engaged in a suitable keeper 7 secured to a corresponding or adjacent portion of the body 1. Thus, with engagement of the pivoted catch 6 in its keeper 7, the cover 4 will be held against swinging or hinged movement with respect to the body 1.

The cover 4 is provided with a longitudinally disposed tapered pocket 8, corresponding in size and shape to the pocket 2 of the body 1 and as illustrated in the Figures 2 and 3, with swinging of the cover 4 to its closed position, will constitute a tapered compartment, circular in cross section.

For the purpose of classifying watch-glasses arranged in the compartments formed in the longitudinally disposed tapered pocket 2, markings generally indicated by the numeral 9, are presented or inscribed upon the upper face of the body 1, as shown in the Figure 1, adjacent said compartments and thus, will indicate to a user of the receptacle the particular compartment in which the different sized watch-glasses are to be placed as well as indicate the particular or desired size of watch-glass with opening of the receptacle for selection of its contents.

Because of the circular cross-sectional formation of the tapered compartment provided by the juxtaposed pockets 2 and 8, it will be understood that the watch-glasses received in the device, will be snugly engaged therein and in consequence, their displacement irrespective of the movement of the receptacle will be prevented. However, with arrangement of the body 1 upon a suitable support and the swinging of the hinged cover 4 to its open position, the watch-glasses will be fully exposed to view of a

person desiring to select some particular size therefrom, or to replenish the store of watch-glasses in their respective classified order therein.

5 Manifestly, the construction shown is capable of considerable modification and such modification, as is within the scope of my claim, I consider within the spirit of my invention.

10 I claim:

A watch-glass receptacle comprising a body, a cover therefor hinged to one portion of the same, said body and cover having complementally shaped longitudinally dis-

posed tapered pockets therein, semi-circular 15 in cross-section and adapted, when arranged in juxtaposed relation, to form a snug compartment varying in diameter throughout its length for watch-glasses, and a plurality of transversely disposed semi-circular partitions arranged in the pockets in said body dividing the same into individual compartments, the adjacent portions of said body having markings thereon, as and for the purpose set forth.

In witness whereof I have hereunto set my hand.

ISAAC MARKS.
